CLAIM

(22) Filed: **Mar. 20, 2000**

We claim the ornamental design for a wall-mounted home network unit, as shown and described.

(51) LOC (7) Cl. **14-02**

DESCRIPTION

(52) U.S. Cl. **D14/299**

FIG. 1 is an isometric view of a wall-mounted home network unit embodying the ornamental design of the present invention;

(58) Field of Search D13/123; D14/356, D14/357, 358, 433, 434, 299; 397/90.01, 93.01, 93.05; 709/223, 224; 359/167

FIG. 2 is a front view of the wall-mounted home network unit of FIG. 1;

(56) **References Cited**

FIG. 3 is a rear view of the wall-mounted home network unit of FIG. 1;

U.S. PATENT DOCUMENTS

FIG. 4 is a side view of the wall-mounted home network unit of FIG. 1, the opposite side view being a mirror image;
